FEED REGULATOR CONTROL FOR
LABELING MACHINES

John Soares, San Leandro, Calif.

Application July 1, 1946, Serial No. 680,683

5 Claims. (Cl. 271—62)

1

This invention relates to an improved means for adjusting the feed of labels—an adjusting means which is conveniently accessible to the operator of the machine.

Conventional labeling machines for labeling cans and similar containers include means which raises a stack of labels in steps; the labels being raised sufficiently in each step to provide labels for a number of cans which follow each other in a continuous stream through the labeling machine. This step feed of the labels must be accurately controlled to compensate for differences in the thickness of labels, which vary mainly because of differences in thickness of the enamel or printing medium on the labels.

In a machine of this type the operator has all controls except this feed regulator at the front of the machine; the feed regulator being at the back of the machine and near the lower end so that it cannot be reached from the front, therefore if the labels are feeding either too much or too little, too early or too late, the containers will either pass through without a label or the labels may be improperly applied or may be torn or otherwise damaged.

With the present types of adjustment, under such conditions the operator must leave the front of the machine, abandoning temporary control thereof, crawl through to the back of the machine, and by using a wrench or pliers, adjust the feed, of course necessitating the closing down of the machine and making all other help idle until the machine is again adjusted to operate properly. It is one of the most important controls and yet the least accessible. The lack of accessibility is the cause of many shutdowns particularly when the machine is reloaded with additional labels though they may be the same batch of labels. In one particular case each shutdown for adjustment of the feed regulator makes eighteen men idle for a period of ten to thirty minutes, and this results in a great loss in production and increase in cost of labeling the containers.

My invention, a simple attachment which can be installed quickly and easily, makes the feed regulator control accessible from the front of the machine so that the label feed is under constant control along with all other controls of the labeling line.

It eliminates all shut-downs due to improper feeding, because any inaccuracy or improper feeding of the labels can be instantly overcome by adjustment from the operator's customary position at the front of the machine.

2

The objects and advantages of the invention are as follows:

First, to provide means accessible from the front of a labeling machine for adjusting the label feed control, at will.

Second, to provide an attachment for a labeling machine which attachment makes the label feed control instantly accessible from the conventional operator's position in front of the machine.

10 Third, to provide means as outlined which can be attached to a labeling machine without change in the machine structure.

Fourth, to provide an attachment as outlined which is simple in construction and operation, 15 easy to install, instantly accessible, and economical to manufacture.

In describing the invention reference will be made to the accompanying drawings, in which:

Fig. 1 is a rear elevation of the related elements 20 of a container labeling machine with the invention applied thereto.

Fig. 2 is a side elevation of the invention.

Only such parts of the labeling machine as are directly involved are shown in the drawings, the 25 labeling machine including a control trip lever 10 which is controlled by the flow of cans 11. Normally the top of the stack of labels 12 projects upwardly above the trip lever 10 so that the body of the can rides on the top label, each can picking up its label following application of the adhesive. 30 As the labels are picked up the stack gradually reduces in height to where eventually the rim 13 of a can touches the trip lever, followed by actual depression of the lever by following cans, which 35 through the connecting rod 14 forces the cross-head 15 down, with the spring 16 drawing down on the control pin 17. The pin 17 is fixed in the rocker arm or pawl lever 18 which terminates at one end in a roller 19 and has a pawl 20 mounted 40 at the other end.

A cam 21 is continuously driven. So long as the stack of labels is high enough to keep the rims of the cans from depressing the lever 10, the lever through the cross-head 15 and block 22 which is 45 slideable in the slot 23 keeps lever 18 in a raised position so that it is not acted upon by the cam 21, but with depression of the lever 10 by a can, the spring 16 draws the lever 18 down so that it cooperates with the cam with the cam advancing 50 the ratchet 24 with each revolution, and this ratchet cooperates with elevating mechanism (not shown) to raise the stack of labels. As soon as the stack has raised to a proper level the cans will no longer strike the lever 10 and advance of the 55 feed will be stopped.

If the distance between the pivot 25 and the pin 17 is not exactly correct the labels will not feed properly, and this is apt to happen at any time because of variations in the thickness of the enamel coating on the labels.

With the conventional adjustment, the arm 25' is coaxial and integral with the screw 26 and the screws 26 and 27 are respectively right and left hand threaded and provided with check nuts 28. A turnbuckle 29 is provided for adjusting the span between the pivot 25 and pin 17, and this adjustment is on the back of the machine and can only be reached by the operator by abandoning his controls on the front of the machine and climbing under the conveyor, loosening the check nuts and adjusting the turnbuckle and retightening the nuts when the adjustment is made, and this adjustment may be necessary at any unexpected moment and possibly a number of times throughout each shift.

My invention consists in providing an offset member with the arm 25' extending upwardly from one end of a base 30, the arm being offset relative to the axis of the bolt 26, and providing a stem 31 to extend above the top of the machine, and this stem terminates at its upper end in an adjusting knob 32, and at its lower end has the screw 26 integral, and with a thrust collar 33 formed at the juncture of the stem and screw with the screw passing through a bore 34 in the other end of the base 30, and a friction member such as a dished spring collar 35 between the base 30 and thrust collar 33, and a pair of check nuts 36 for drawing and locking the base against axial movement while permitting rotative adjustment; the spring cap 35 maintaining adjustment throughout a considerable period of operation.

Thus the adjustment is under instant control of the operator from his normal station in front of the machine, and shutdowns are entirely eliminated where due to improper feeding of the labels. If the operator requires a quick advance of labels, he need only tap the knob 32 to depress the lever 18 so that the cam 21 will advance the ratchet, and he can by slowly turning the knob in one direction or the other as occasion may require, maintain proper adjustment with correct feeding of the labels and without ever leaving the front of the machine.

The friction between the nuts 36, washer 35 and collar 33 will maintain any adjustment while permitting instant adjustment at any time. It eliminates idle periods, unlabeled cans, and damaged labels, and a continuous flow of correctly and uniformly labeled containers is assured.

I claim:

1. Label feed regulator adjusting means for a labeling machine having a turnbuckle, a trip lever operable by the elements to be labeled and a cam actuated pawl lever and a connection from said pawl lever to said turnbuckle comprising an adjusting member threadedly cooperative with said turnbuckle and having an extension to the top of the labeling machine and terminating in a handgrip for adjustment of the length of the operative connection at will, and a second connection from said adjusting member to said trip lever and having a passage with said adjusting member rotatable therein and maintained against relative axial movement.

2. In a labeling machine having a feed regulator including a trip lever, and a cam actuated pawl and a connecting rod connecting said trip lever and cam actuated pawl; remote con-

trol adjusting means for adjusting the length of said connecting rod comprising an adjusting element threadedly intermediate connecting said connecting rod and extending to the top of the machine and accessible from the front of the machine for manual adjustment of the length of the connecting rod at will.

3. A structure as defined in claim 2 in which said connecting rod includes a turnbuckle, and an offset member; said adjusting means comprising a shaft threadedly associated at one end with said turnbuckle and rotatably associated with one end of said connecting rod and extending to the top of the machine within reach from the front of the machine for control thereof, and with the other end of the offset member having connection with said trip lever.

4. A remote control attachment for adjustment of the feed regulator of a labeling machine having a trip lever and a cam actuated feed pawl and an operative connection therebetween with intervening turnbuckle comprising; a shaft terminating at one end in a threaded portion for adjustment in said turnbuckle, and in turn terminating in a shoulder and having a knob at the other end and extending above the top at the rear of the machine; an off-set connection having a bore at one end for said shaft and a connection at the other end for the portion of the operative connection to the trip lever; a friction member between said shoulder and the off-set connection to retain relative adjustment of the shaft and the off-set connection, and locknuts for retaining the shaft and off-set connection against relative axial movement and for adjusting the resistance of said friction means.

5. A remote control attachment for the label feed regulator of a labeling machine having a trip lever actuatable by elements to be labeled and a cam actuatable pawl lever and relatively inaccessibly located at the back of the machine, comprising; a turnbuckle, a connection from said cam actuatable pawl lever to said turnbuckle, an offset member having a bore formed through one end and an upwardly extending arm at the other end and a connection from said upwardly extending arm to said trip lever, an adjusting stem threadedly adjustably cooperating with said turnbuckle and frictionally rotatable in said bore and retained against axial movement in said bore and extending upwardly therefrom to a plane above the top of the machine and terminating in a knob for adjustment of the length of the combination of connections from the trip lever to the cam actuatable pawl lever, from the front of the machine at will, whereby said feed regulator is under immediate and constant control from the front of the machine.
